LETTER TRAY

Eric Gronemeyer, Pompton Plains, N. J., assignor to Zephyr American Corp., a corporation of New York

Application October 17, 1947, Serial No. 141,969

Term of patent 7 years

(Cl. D74—1)

To all whom it may concern:

Be it known that I, Eric Gronemeyer, a citizen of the United States of America and a resident of the city of Pompton Plains, in the county of Morris and State of New Jersey, have invented a new, original, and ornamental Design for a Letter Tray, of which the following is a specification, reference being had to the accompanying drawing, forming a part thereof.

Fig. 1 is a plan view of a letter tray showing my new design.

Fig. 2 is a side view thereof, and

Fig. 3 is a front view thereof.

I claim:

The ornamental design for a letter tray, substantially as shown.

ERIC GRONEMEYER.
